UNITED STATES PATENT OFFICE.

CHARLES L. RAYFIELD, OF CHICAGO, ILLINOIS.

STRAINER.

1,160,653.

Specification of Letters Patent. Patented Nov. 16, 1915.

Application filed August 30, 1911. Serial No. 646,818.

To all whom it may concern:

Be it known that I, CHARLES L. RAYFIELD, a citizen of the United States, and a resident of the city of Chicago, county of Cook, and State of Illinois, have invented certain new and useful Improvements in Strainers; and I do hereby declare that the following is a full, clear, and exact description of the same, reference being had to the accompanying drawings, and to the numbers of reference marked thereon, which form a part of this specification.

This invention relates more particularly to strainers for fluid circulating systems; for example, the gasolene supply pipe leading from the gasolene tank of the carbureter of a gasolene engine.

A very small amount of dirt finding its way into a carbureter, will clog the same sufficiently to either shut off the supply altogether, or to such an extent as to seriously affect the operation and reliability of the engine until the dirt is removed. Frequently also, a small quantity of water is contained in the gasolene, and this also reaching the carbureter, causes stoppage, or irregular working of the engine or motor.

The object of this invention is to afford a strainer of such a construction as to exclude oil, dirt, and refuse from the supply line to the carbureter, and to afford a receptacle or trap therefor to collect the same below the normal flow of the gasolene.

It is also an object of the invention to afford a construction in which water may be separated from the gasolene and the gasolene only permitted to flow to the carbureter.

It is an important object of the invention to afford a sufficiently large collecting chamber for water or refuse below the normal flow of the gasolene, to avoid any disturbance of the contents near the bottom of the receptacle by the flow of the gasolene therethrough.

Finally it is an object of the invention to afford a construction of the class described, provided with a discharge or waste cock permitting the collecting chamber to be drained or discharged from time to time, and obviating the necessity of disconnecting from the gasolene feed pipe for the purpose of cleaning.

The invention consists in the matters hereinafter described and more fully pointed out and defined in the appended claims.

In the drawings: Figure 1 is a central vertical section of a preferred form of a device embodying my invention. Fig. 2 is a view in elevation thereof. Fig. 3 is an enlarged bottom plan view of the strainer, showing the same removed from its casing. Fig. 4 is a fragmentary vertical section thereof.

As shown in the drawings: A casing is constructed of cast or any suitable metal or material comprising an upper cylindric bored portion 1, and a lower portion 2, providing therein a globular or enlarged settling and collecting chamber or trap. Extending downwardly from the bottom of said lower portion 2, of the casing is a cylindric boss 3, having an aperture or passage 4, therein, in which is threaded a waste cock 5. Said waste cock for convenience, is shown as a simple type of plug cock, the plug of which is engaged by a spring 6, which acts at all times to hold the same seated to prevent leakage of the fluid therearound. A bracket or arm 7, is secured on said boss 3, and is adapted for attachment to any suitable support to carry the weight of the device independently of the gasolene supply line.

Extending into the cylindric bore in the upper part of the casing, is a strainer head 8, which fits closely in said bore at its bottom and is provided with a downwardly directed flange 9, around its periphery, across which is secured by soldering or other suitable means, a fine metal gauze strainer 10. Integrally connected with said strainer head, is an upwardly directed, tubular stem 11, which opens through said head, and is provided with oppositely directed apertures 12, therein opening into the upper chamber afforded by the cylindric bored portion of the casing, and, as shown, a cover cap 13, integral with the stem 11, seats upon a packing washer 14, of any suitable material on the upper end of the casing, to seal the same, as shown in Fig. 1. A clamp 15, engages beneath a peripheral flange 16, at the top of said casing, and is provided with a central pressure screw 17, which bears on said head or cover plate 13, and acts to hold the same firmly seated at all times to close said upper chamber.

An internally threaded passage 18, is provided in one side of the casing, and conveniently a little above the strainer head, as shown in Fig. 1, and extends downwardly

into the lower or collecting chamber, and threaded thereinto, is a pipe or nipple 19, adapted to be connected by means of any suitable union 20, with the gasoline supply pipe leading from the supply tank. Opening into the upper chamber substantially opposite the passage 18, is a passage 21, and threaded therein is a nipple or connection 22, adapted to afford connection by means of

10 a suitable union 23, with that portion of the supply pipe leading to the carbureter.

The operation is as follows: The gasoline or other fluid from the source of supply, is admitted through the passage 18, into the 15 lower or collecting chamber and filling the same, the gasoline or other fluid (which is lighter than any water contained therein) passes upwardly through the screen 10, through the passage in the stem, through the 20 lateral apertures 12, and substantially fills the upper chamber and flows therefrom to the carbureter through the nipple or pipe 23, and its connections. Any dirt or refuse is arrested by the screen, and, owing to the 25 relatively large size of the collecting chamber or trap, soon falls to the bottom of the lower compartment. This is facilitated owing to the fact that the strainer affords a large surface for the flow of the gasoline 30 therethrough, and the flow is not concentrated at any one point thereon. In consequence, the upward pressure and flow through the screen at any point, is not sufficient to force the dirt therethrough, even 35 though the dirt be quite fine. The water, being heavier than the gasoline or other fuel oil, falls to the bottom of said compartment, and there remains until, together with the dirt and refuse collected (if any), 40 it may be drained from said compartment by the opening of the waste cock 5.

Should it ever be deemed desirable to inspect the interior of the device, it may be readily accomplished without disconnecting 45 from the supply pipe by releasing the clamp 15, by the retraction of the screw 17. When this is done, the strainer head may be lifted from its chamber, affording access to the interior of the casing, and permitting inspection 50 of all parts thereof, after which, of course, the strainer head is restored to place, and the clamp reengaged in place, and the device is ready for use as before described.

Details of the construction may, of course, be varied, as may the relative sizes of the 55 chambers in the casing, and the particular connections described, for I have shown but one (and that a preferred) form of the invention, and I therefore do not purpose limiting the patent granted otherwise than 60 necessitated by the prior art.

I claim as my invention:

1. A casing affording an upper chamber and a larger lower collecting chamber or trap, a dividing wall between said chambers, 65 a peripheral, downwardly extending flange thereon, a fine wire gauze screen secured on said flange below the dividing wall, a tubular stem connected in the dividing wall and ported to discharge into the upper chamber, 70 a removable cover for the upper chamber, an induction pipe connected to discharge into the lower or collecting chamber, and an eduction pipe connected to discharge from the upper chamber. 75

2. A casing affording an induction chamber and an eduction chamber, a dividing wall between said chambers, a peripheral flange thereon, extending into the induction chamber, a fine wire gauze screen secured on 80 said flange in the induction chamber, a pipe connected centrally in said wall and ported to discharge into the eduction chamber, a removable head or cover for the eduction chamber, an induction pipe connected to discharge into the induction chamber, and an eduction pipe connected to discharge from the eduction chamber. 85

3. In a device of the class described the combination with a casing affording a trap 90 or collecting chamber, of an integral tangential induction passage communicating therein at its top, a downwardly facing strainer member comprising a flanged disk, a screen secured around the flange, a central 95 apertured shank extending upwardly therefrom affording an eduction passage from said chamber, and a cover for the casing integral with said shank.

In testimony whereof I have hereunto 100 subscribed my name in the presence of two subscribing witnesses.

CHARLES L. RAYFIELD.
